F. P. PRENDERGAST

BROOM

Filed Sept. 14, 1921

UNITED STATES PATENT OFFICE.

FRANK P. PRENDERGAST, OF KERSEY, PENNSYLVANIA.

BROOM.

Application filed September 14, 1921. Serial No. 500,477.

To all whom it may concern:

Be it known that I, FRANK P. PRENDERGAST, a citizen of the United States, residing at Kersey, in the county of Elk and State of Pennsylvania, have invented certain new and useful Improvements in Brooms, of which the following is a specification.

This invention relates to improvements in brooms, brushes, and similar articles comprising a head of straw or other material, and a handle of wood, and more particularly to that class of such devices in which the handle is separably connected with the head.

It is a well recognized fact that brooms which have their heads and handles permanently secured together cannot be conveniently packed for shipment because of the odd shape of the articles, and during shipment the bundles are liable to become broken or the brooms damaged. Also in the use of the ordinary broom, when the head becomes considerably worn, the entire article is usually discarded notwithstanding the fact that the handle may be in perfect condition.

Therefore, the present invention has as its general object to provide a novel means whereby the head and handle of a broom or similar article may be readily assembled and separated so that these parts may be separately manufactured and likewise separately packed for shipment and sold. Likewise it is an object of the invention to avoid the waste incident to throwing away of the handle of the ordinary broom when the head thereof becomes worn, the device of the present invention permitting of the repeated use of the handle by the substitution of one broom head for another as these parts become so worn as to become unfit for further use. Also the invention is intended to effect a saving to the retail dealer as such articles as the broom head alone may be wrapped in a comparatively small package and will ordinarily be carried from the place of business by the purchaser whereas it is seldom that the purchaser will carry away a complete broom after purchase.

Another object of the invention is to so construct the connecting means for the head and handle of the broom that, while the parts may be readily separated when required, they may ordinarily be locked against separation, and the connection rendered rigid.

A still further object of the invention is to provide a connection of the class referred

to which will impart to the broom a neat and sanitary appearance.

The invention also has as its object to economize in material in the manufacture of articles of this class inasmuch as by the employment of the connection embodying the invention, the wooden handle may be formed shorter than is customary.

In the accompanying drawings:

Figure 1 is a vertical transverse sectional view through a broom embodying the present invention;

Figure 2 is a vertical sectional view on the line 2—2 of Figure 1;

Figure 3 is a horizontal sectional view in detail on the line 3—3 of Figure 1;

Figure 4 is a detail sectional view taken substantially on the line 4—4 of Figure 2 illustrating the parts partly separated;

Figure 5 is a detail view of one of the parts illustrated in Figure 4;

Figure 6 is a plan view of the blank from which the socket member of the device is formed.

In the drawings, the numeral 1 indicates in general the head of a broom and the numeral 2 the handle, these parts being designed to be connected by the device embodying the invention. The handle 2 may be of the usual form and is adapted to be fitted at its lower end into a socket member carried by the broom head 1, the said end of the handle, for a purpose to be presently explained, being turned down to form a rounded head 3 and a neck 4 of smaller diameter than the head.

The socket member referred to above is indicated in general by the numeral 5 and the same comprises a cylindrical sleeve 6 formed from a blank such as illustrated in Figure 6 of the drawings, the blank being initially substantially rectangular in form and being rolled to the required shape and its longitudinal edges brought together. The head 1 which is built up of broom straws, is constructed about the socket member 5 as best shown in Figure 1 of the drawings, and the upper ends of the broom straws are bunched and tightly bound about the upper portion of the said socket member. The straws are bound by a wire 7, one end of this wire being anchored to tongues 10 which are struck out from the lower end portion of the said socket member and take the place of the usual tack driven into the handle of

the ordinary broom, the opposite end of the wire, after it is wrapped around the straw, being anchored to other tongues 8 which are struck out from the upper end portion of 5 the said socket member.

The upper end of the sleeve 6 of the socket member projects above the upper end of the broom head 1 a short distance and is open so as to receive the lower end of the handle 10 2, the parts being so proportioned that the handle will fit snugly within the socket member when inserted into place. In order that the handle may be retained in place within the socket member, resilient locking 15 tongues 11 are stamped out from the blank from which the socket member is formed and are deflected inwardly along curved lines so as to project into the socket member 6 and frictionally engage the neck 4 of the handle above the head 3 for the purpose 20 stated.

In order to cover the upper portion of the broom head 1 which is bound by the wrapping 7, there is provided a cap member 25 which is indicated in general by the numeral 12 and which comprises a hollow bulged body 13 adapted to the fitted down over the handle 2 to fit over the said wrapped or bound portion of the broom head 1 as best 30 shown in Figure 1 of the drawings. The upper portion of the body 13 is contracted to form the neck 14 adapted to surround the upper end of the socket member 6 and its upper edge may be flanged inwardly, 35 as at 15, so as to adapt the neck to snugly fit about the handle and over the upper end edge of the sleeve 6. The cap member 12 is designed to be permanently held in place upon the handle and this is done 40 preferably by the employment of a screw eye 16 which is of the ordinary form except that its shank 17 is, for a purpose to be presently explained, preferably notched or cut away at diametrically opposite sides 45 as indicated by the numeral 18. The screw eye 16 is fitted through an opening 19 formed in the neck 14 of the cap member 12 and is threaded into the handle 2. At this point it will be evident that when the cap member 12 has been secured to the handle 50 at a point suitably elevated above the lower end of the handle, the handle may be fitted into the socket member 6 and in thus assembling the parts the cap member will be passed downwardly over the wrapped upper 55 end of the broom head thus covering this end and concealing the wrapping 7. It will also be evident that inasmuch as the cap member serves to conceal the wrapping 7 this wrapping may be applied with less care 60 than is ordinarily required to be used, and may constitute fewer turns of wire than ordinarily given.

In order to accommodate the shank of the 65 screw eye 16 and at the same time provide

means whereby the handle may be securely locked to the socket member 6 against withdrawal from the same, the blank from which the socket member is formed is provided in its upper corners with notches 20 and has its 70 said corners cut diagonally above the notches, as indicated by the numeral 21, so that when the blank is formed up into the completed socket member, this member will be provided at its upper end with an approximately circular opening 22 and with a tapered throat 23 providing an entrance to the said opening 22 and opening through the upper end edge of the sleeve 6 of the socket member. By reference to Figure 4 of the 75 drawings it will be understood that when the parts are to be assembled, the screw eye 17 may be given a backward quarter turn so as to bring the notches 18 into vertical position or in other words parallel to the axis of 80 the broom handle and as the shank 17 between the notches is of a thickness slightly less than the width of the throat 23 at its point of communication with the opening 22, the shank of the screw eye may pass down 85 into the opening 22 as shown in the said Figure 4, as the handle 2 is fitted into place in the socket member 5. When the shank 17 of the screw eye has been introduced into the opening 22, the screw eye is given but a quarter turn so that the portion of the shank between the notches 18 will be positioned across the said opening and as this portion of the shank is of a width greater than the width of the throat 23, the screw eye shank 90 will be retained within the opening. If found desirable, this means alone may be employed for the purpose of retaining the handle within the socket member, in which event the locking tongues 11 may be dispensed with as also the head 3 and neck 4 at the lower end of the handle 2, and the said locking tongues may be bent inwardly beneath the lower end of the handle.

Having thus described the invention, what 95 is claimed as new is:

1. In a broom, the combination with a broom head and handle, of a handle-receiving socket in the head consisting of a tube 115 having lateral tongues at its ends and constructed near its upper end with an opening, and a restricted entrance leading from its upper edge into said opening, a locking member carried by the handle and constructed to pass through said entrance into said opening and be turned into locking engagement with the opening, and a binding wire wrapped around the upper end of the head and having its ends anchored on the tongues at the ends of the tube.

2. In an article of the class described, a socket member comprising a tubular body provided at its upper end in its wall with an opening and with a throat communicating with the opening and of a width less 120 130

than the diameter of the opening, a handle member removably fitted at one end into the socket member, and a locking element rotatably carried by the handle and having a portion dimensioned to pass through the throat and into the opening in one position of the said locking element and to extend transversely within the opening in another position of the locking element.

3. In an article of the class described, a socket member comprising a tubular body provided at its upper end in its wall with an opening and with a restricted throat com-

municating with the opening, a handle removably fitted at one end into the said socket member, and a locking element rotatably carried by the handle and having a shank provided in its opposite sides with notches to receive the walls of the throat in one position of said element to permit the shank of the element to pass into the said opening, the shank of the element between the notches being of a width greater than the width of the throat.

In testimony whereof I affix my signature.

FRANK P. PRENDERGAST. [L. s.]
